UNITED STATES PATENT OFFICE.

HENRY C. GAUSS, OF WASHINGTON, DISTRICT OF COLUMBIA.

CRYPTOGRAPHY.

1,379,551.

Specification of Letters Patent. Patented May 24, 1921.

Application filed September 17, 1920. Serial No. 410,919.

To all whom it may concern:

Be it known that I, HENRY C. GAUSS, a citizen of the United States, residing at Washington, in the District of Columbia, 5 have invented certain new and useful Improvements in Cryptography, of which the following is a specification.

This invention relates to cryptography and has for an object to provide a system where- 10 in allotments of alphabetical letters are represented by the permutation of the units of a pre-determined number of like arbitrary symbol groups, the number of units in each group being less than the number of letters 15 in the alphabet.

It is well known that in the English, or any other language, there are certain groups of letters which are impossible and unused. It is also well known that there are other 20 groups, possible, but very little used. Such groups are grouped together or with com- monly used groups thereby reducing the number of permutations of alphabet letters to a given number very much below the 25 theoretical permutations.

The present invention, while capable of a very wide range of usages, and exemplified in a number of different manners, is primarily intended to use in conjunction 30 with punched cards which, in turn, are sorted by automatic sorting machines into sequences alphabetically, numerically, or chronologically arranged.

One principal use of the system will be in 35 city directory work and the invention will be explained herein in accordance with that work. The modern city directory employs at least three major divisions, to wit, that have the surnames in alphabetical order, similar 40 names being differentiated by given names and initials, second, a division of streets, ar- ranged alphabetically, and subdivided nu- merically; and, third a division of classified occupations, arranged alphabetically and 45 subdivided alphabetically according to the names appearing under those classifications. It is desirable to be able to assort the cards carrying the data as quickly as possible from one such arrangement to another, to 50 minimize the time employed in getting out and publishing the directory. The present system provides the use of a card upon which the canvasser writes the data for each entry, or such data is copied to a card at the 55 office from the canvasser's returns, this being a mere matter of business system,

resulting in a card having the data written thereon, and a field or a plurality of fields properly designated for use in conjunction with a punching machine.

The present day punching machine is ar- ranged to punch vertical columns of twelve 60 positions, and a pre-determined number of columns. The present disclosure is of a card having such a pre-determined number 65 of columns of twelve positions each. In these columns the hereinbefore mentioned arbitrary symbol units are grouped. For convenience in memorizing and designating, numerical digits are preferably employed. 70 As there are only ten numerical digits these must be supplemented by other arbitrary symbol units. In the disclosure the symbol units (–) and (x) are employed. These two symbol units together with the numerical 75 digits, will be referred to herein as digits, it being understood, however, that the word digits is employed only as illustrative and the actual numerical digits may all be re- placed by arbitrary symbols and such 80 nomenclature is no limitation upon such use.

Also the employment of twelve digits is selected only to correspond to the present day punching machines and the system is capable of variations and permutations to 85 meet the requirements of a lesser or greater number of symbol units as future punching machines may make desirable.

It is obvious that the permutations of a given number of groups of twelve units each 90 will be much less than the permutations of a like number of groups containing all of the alphabet letters. It is the allocation of the alphabet letters to produce allotments to correspond in number to the permuta- 95 tions of the pre-determined number of ar- bitrary symbols and the system of designat- ing the allotments by such permuted units, irrespective of the number of units em- ployed or the units themselves or the man- 100 ner of designating such symbols, which forms the basis of this invention.

In the drawings Figures 1 to 12 inclusive have been so designated simply for con- 105 venience of reference, and may not in use be so divided, as the chart represented by these 12 figures may, if found convenient, be employed as a continuous chart or the several classes, represented by these arbi- trarily assigned figure numbers, may be 110 subdivided and appear upon separate cards.

Figs. 13, 14 and 15 are arbitrarily select-

ed representations of the manner of use as employed in city directory work.

The class symbol unit does not, standing alone, designate a letter, as for instance, 5 the class symbol (-) may be the initial symbol unit of an allotment of letters beginning either with A or B, while the letter B, in turn, falls within two classes, designated respectively by the symbol units (-) and (x). 10 Likewise the section symbols, standing alone, do not designate any definite two letters as, for instance, the section symbol (- -) may designate aa, ab, or ac according to the third symbol unit, which is the differentiating 15 symbol unit.

The complete symbol may or may not designate a fixed group of letters. The symbol (- - x) at 20 in Fig. 1 designates an allotment wherein the first two letters are aa 20 and the third letters, any letters of the alphabet. As distinguished from this, the symbol (- xo), at 21 in Fig. 1, does designate a fixed group of letters acl. Wherever, therefore, the symbol (- xo) appears, the 25 fixed combination of letters acl is always designated. This applies throughout the chart as will be noted. In other words, certain commonly used single letters and combinations have been allotted for specific designation by specific grouping of digits and the little used combinations have been allotted into defined alphabetical ranges. As, for instance, at 22 in Fig. 1, the symbol (-7x) indicates the range axm-axz. Following ax, combinations between m and z are 30 very rare, so that but few words will fall within this range, requiring differentiation. It has been found that the majority of words may be differentiated by their first syllables. 35 When this is not possible a further differentiation is provided for in the present system. It is not the basic plan of this invention to provide cards, when punched, to be read accurately from such punchings, although in 40 many instances this will be possible. The basic idea is to provide cards which will be sorted by automatic sorting machines into their proper alphabetical order.

To illustrate, Figs. 13, 14 and 15 represent 45 cards which have been punched in accordance with the present system, no attempt having been made to show these cards to any particular scale or proportion. Cards are shown having fields for punching data of the 50 surname, given name, city, street, number, and occupation. At the left a field is shown for writing, printing or otherwise displaying the complete data. The punching of these cards adds nothing to the data displayed but 55 facilitates the mechanical sorting with the well known rapidity of mechanical sorting machines into such classes, sub-classes, groups and sequence as the requirements of use make desirable. For instance, it would 60 be natural to first sort the cards to the sur-

name appearing in the left hand field. Similar names have been chosen, also very similar data throughout for the purpose of disclosing the manner of differentiation. At Fig. 13 the surname as indicated at 23 is 70 Johns. At Fig. 14 as indicated at 24, the name is Jones, the same being true of Fig. 15 at 25. All of these surnames, therefore, begin with the two letters Jo and are differentiated by the third letter. By referring to 75 Fig. 6, at 26, it will be noted that the symbol 304 indicates a fixed combination of letters Joh. The first field is, therefore, punched 304 as indicated at 27 in Fig. 13. The combination Jon, falls within the range 80 jol-joq indicated at 28 in Fig. 6. The surname fields at Figs. 14 and 15 are, therefore, punched the symbol of this range jol-joq, which is 306. The surnames Johns and Jones are, therefore differentiated in the 85 third column as indicated at 27 and 29 in Figs. 13 and 14.

Given names all beginning with Sa have been chosen, to disclose the manner of differentiation. At Fig. 13, the given name is 90 Sarah. The group Sar has a definite symbol, 728, as indicated at 30 in Fig. 10. The given name Field 31 at Fig. 13 is, therefore, punched the symbol of Sar, to wit, 728. The group Sam falls in the range sam-saq and 95 is designated as indicated at 32, in Fig. 10, by the symbol 727. The given names Samantha, at 33 in Fig. 14, and Samuel, at 34 in Fig. 15, are, therefore, punched the symbol 727. It is necessary to differentiate between Samantha Jones and Samuel Jones, which, up to this point, have received the same symbols. The fourth letter in these 100 two names will differentiate, in Samantha being a and in Samuel being u. The fourth column of field 33 is punched the symbol which includes A in the general class, to wit, (-) as indicating the class at Fig. 1. The u of Samuel is designated by punching the numeral of the class in which u appears, to 110 wit, the numeral 8 as indicated at 35 in Fig. 11. It should be noted that the unit (-) does not, alone, represent a or the unit 8 represent u but the unit (-) will sort before the unit 8 and the cards will therefore 115 be differentiated in their correct alphabetical order.

In passing these cards through the automatic sorting machine they will all be sorted 120 first, of course, from a multitude of other cards, to the first digit in the first column 3. They will, therefore, all fall in the same receptacle. The second sorting, to the second column, will have a like result, all falling in the same receptacle under the designation O. 125 Sorting to the third column will differentiate between Johns and Jones, the Johns card falling in box 4, while the two Jones cards will fall in box 6. Passing the two Jones cards, of course, with a great number 130

of others, through the machine will sort to the first column in fields 33 and 34; the second run to the second column, the third run to the third column, these two cards still 5 continuing to drop in the same box. The run to the fourth column, however, differentiates these cards, and they are finally arranged with Samantha preceding Samuel.

Of course, in ordinary city directory work 10 no field for the name of the city would be employed, as all would be residents of the same city. For gazetteer work the name of the city would be necessary. A field has been shown at Figs. 13 and 14 for this purpose 15 and names of cities have been selected, having the same first two letters, showing the manner of differentiation. In fields 36, 37 and 38, Washington, Waterbury and Waverly have been represented and differentiated. 20 The combinations was and wat of Washington and Waterbury, respectively. fall in the same range, indicated at 39 in Fig. 12, was-wat, with the symbol 906. The fields 36 and 37 are, therefore, punched this 25 symbol, 906, but this indicates either was or wat. The final S or T is, therefore, designated by the class number including S, shown at 40 in Fig. 10 as the numeral 7. The final punch designation for Washington 30 is 9067. The e of Waterbury falls within group 8 indicated at 35 in Fig. 11 so that the final punch designation of Waterbury is 9068, which differentiates it from Washington.

35 Waverly presents the first three letters Wav, which falls within the range wav-waw at 41 in Fig. 12, the symbol being 908 and the field 38 so punched.

The streets, of the three cards, have been 40 arbitrarily designated as Euclid, Eureka and Eutis, all beginning with the letters eu. The range including eu is range eu-euz, indicated at 42 in Fig. 4, the symbol of which is 1x0. This, therefore, includes any third 45 letter. The third letter will, therefore, be employed to differentiate and the class designation is employed for that purpose. The third letter c of Euclid falls in the class BEW-CZZ, with the symbol (x) as indicated at 43 in Fig. 2. The r, the third letter of Eureka, falls within the class designation P-RIL, with the symbol 6 designating the same as indicated at 44 in Fig. 9. The third 50 letter s. of Eustis, falls within the class designation RIM-SZZ with the symbol 7 as indicated at 40 in Fig. 10. The streets Euclid, Eureka, Eustis are differentiated in the fields 45, 46 and 47 by the third column punch (x) (6) and (7), respectively, so that 55 the sorting machine will sort them in the order of their third letters.

The street number appearing in fields 48, 49 and 50 simply punch the numerals and no explanation is required.

60 65 For occupations, claims, clairvoyant and

clerk have been selected, all beginning with the two letters cl to disclose the manner of differentiation. All fall for their first three letters within the range cl-clz as indicated at 51 in Fig. 2 with the symbol x6x. It 70 is necessary to go further, than the first three colmuns, to differentiate. The third letters are designated by the same punch symbol in each case and are, therefore, taken as a starter for the differentiation. Aim of claims 75 and Air of clairvoyant fall within the range aim-air as indicated at 52 of Fig. 1 with the symbol -15. So far, as is represented by six columns, claims and clairvoyant are punched the same. It is the third letter of 80 the second group m and r, respectively, which must be employed to differentiate. M falls in the class designation LOG-MZZ with the symbol 4 as indicated at 53 in Fig. 7, while r, the third letter of the second 85 group, falls in the class designation RIM-SZZ, with the symbol 7, as indicated at 40 in Fig. 10. The seventh column, therefore, differentiates, claims being punched 4 and clairvoyant 7. For clerk the third letter, e, 90 falls in the class designation D-EPZ with the symbol o as indicated at 54 in Fig. 3.

The manner of differentiating words for names, cities, streets, occupations, or any other required or desired data, is apparent. 95

Assume that, for gazetteer purposes, it is desirable to arrange the data, first under cities alphabetically arranged, the sorting machine is set to sort to the third punch field in the usual well known manner. The cards, 100 differentiated as above stated, will be by the sorting machine arranged in their proper alphabetical order. If it is desired to arrange next under the occupation, the sorting machine is set to sort to the sixth field, or 105 if it is desired to arrange under the names alphabetically, the machine is set to sort the first and second fields. After the first arrangement, the cards are all again thrown into the sorting machine to sort to some 110 other arrangement. For instance, if the first arrangement has been under city designations and it is desired to run an a to z arrangement of the names, irrespective of residence, the machine will so sort. In fact, 115 once punched, the cards will be mechanically sorted to any of the data appearing thereon.

In ordinary hand sorting of directory data, for instance, it is necessary to await the complete returns of the canvassers before sorting can be completed. With this system the work of the canvassers one day may be punched at the office the following day, and when the work of the canvassers is completed the cards are all substantially 120 completed for mechanical sorting which will be done with the well known expedition.

While the transferring of the data to the cards in accordance with this system has been here designated as "punching" it is to 130

be understood that actual punching is only resorted to to comply with the present use of certain sorting machines, and that any other means of designating the data will 5 fall equally within the scope of this invention.

The mechanical sorting of the cards is something wholly outside of the present system, being a well known mechanical expedient and the machines at present in use 10 capable of adjustment for sorting the cards in accordance with this application. The designation of the symbols by means other than punching, to correspond to any requirements of any sorting machine or hand sorting, will fall fully within the scope of the 15 present invention.

The arbitrary symbols, selected for and disclosed in this particular application, have 20 been found to meet the requirements of a system of the scope referred to, but the present invention is not limited to the identical symbols or the identical number of units or groups or the identical allotments combinations or groups of letters designated by 25 the, or any of the symbols so employed, and includes different allotments of letters as the exigencies of use may make necessary or desirable, and the employment of other symbols and in greater or lesser numbers as the 30 mechanical exigencies may indicate as desirable.

I claim:

1. A system of cryptography comprising 35 arbitrary allotments of letters, said allotments comprising a number of groups, each derived from a predetermined number of alphabets and assigning to each such allotment a symbol comprising a permutation of 40 the units of a like number of groups of arbitrary symbol units, each group containing units less in number than the letters of the 45 alphabet.

2. A system of cryptography comprising 50 arbitrary allotments of letters, said allotments comprising a number of groups, each derived from a predetermined number of alphabets, assigning to each allotment a symbol comprising a permutation of the 55 units of a plurality of like number of groups of arbitrary symbol units each group containing units less in number than the letters of the alphabet, employing a card displaying a predetermined number of said groups 60 of symbol units and designating thereon the units allocated to complete the symbol.

3. A system of cryptography comprising 65 arbitrary allotments of letters, said allotments comprising a number of groups, each derived from a predetermined number of alphabets, assigning to each allotment a symbol comprising a permutation of the units of a plurality of like number of groups of arbitrary symbol units each group 70 containing units less in number than the

letters of the alphabet, employing a card displaying a predetermined number of separate fields each having a predetermined number of said groups of symbol units and designating thereon the units allocated to 75 complete the symbol.

4. A system of cryptography comprising the employment of a group of arbitrary symbol units less in number than the letters 80 of the alphabet, permuting the units of a predetermined number of said groups to form symbols and arbitrarily assigning to each symbol an alphabetical allotment, said allotment comprising a number of groups, each derived from employing the letters of a plurality of alphabets corresponding to the 85 number of groups of symbols.

5. A system of cryptography comprising the employment of a group of arbitrary symbol units less in number than the letters 90 of the alphabet, permuting the units of a predetermined number of said groups to form symbols, arbitrarily assigning to each symbol an alphabetical allotment, said allotment comprising a number of groups, each derived from employing the letters of a plurality of alphabets corresponding to the 95 number of groups of symbols, employing a card displaying a predetermined number of said groups of symbol units and designating thereon the units allocated to complete the symbol.

6. A system of cryptography comprising the employment of a group of arbitrary symbol units less in number than the letters 100 of the alphabet, permuting the units of a predetermined number of said groups to form symbols, arbitrarily assigning to each symbol an alphabetical allotment, said allotment comprising a number of groups, each derived from employing the letters of a plurality of alphabets corresponding to the 105 number of groups of symbols, employing a card displaying a predetermined number of separate fields each having a predetermined number of said groups of symbol units and designating thereon the units allocated to 110 complete the symbol.

7. A system of cryptography consisting in arranging alphabet letters into groups 115 each having a predetermined number of constant letters and a variable letter, assigning to the group an arbitrary symbol and providing a further symbol for differentiating between the variable letters in different words.

8. A system of cryptography consisting in arranging groups, each containing a predetermined number of invariable letters secured as the permutation of the letters of 120 a number of alphabets and a predetermined alphabetical range, assigning to each group an arbitrary symbol and providing a further symbol employed when necessary to differentiate letters within the range.

9. A system of cryptography consisting in arranging commonly used groups of alphabet letters, other groups having a predetermined alphabet range including lesser used groups, assigning arbitrary symbols to each of the groups and providing a further symbol to differentiate between letters falling within the range. 5
10. A system of cryptography consisting in arranging alphabet letters into fixed groups and elastic groups, assigning an arbitrary symbol to each group and providing other symbols for differentiating between the elastic groups. 10
11. A system of cryptography consisting in dividing the letters of the alphabet into classes less than the number of letters in the alphabet, assigning to each class an arbitrary symbol unit, dividing the classes into sections less than the number of letters in the alphabet, assigning to each section an arbitrary symbol unit, dividing the sections into groups less than the number of letters in the alphabet, assigning to each group an arbitrary symbol unit and collocating the class, section and group units to form a complete symbol. 15
12. A system of cryptography consisting in dividing the letters of the alphabet into classes less than the number of letters in the alphabet, assigning to each class an arbitrary symbol unit, dividing the classes into sections less than the number of letters in the alphabet, assigning to each section an arbitrary symbol unit, dividing the sections into groups less than the number of letters in the alphabet, assigning to each group an arbitrary symbol unit, employing a card displaying a predetermined number of groups of unit symbols and designating thereon the units collocated to complete the symbol. 20
13. A system of cryptography consisting in dividing the letters of the alphabet into classes less than the number of letters in the alphabet, assigning to each class an arbitrary symbol unit, dividing the classes into sections less than the number of letters in the alphabet, assigning to each section an arbitrary symbol unit, dividing the sections into groups less than the number of letters in the alphabet, assigning to each group an arbitrary symbol unit, employing a card displaying a predetermined number of separate fields, each having a predetermined number of groups of unit symbols and designating thereon the units collocated to complete the symbol. 25
14. A system of cryptography consisting in selecting a predetermined number of arbitrary symbol units less than the number of letters in the alphabet, dividing the alphabet into classes equal to the number of symbol units, assigning one of the units to each of the classes, dividing the classes into
- a like number of sections, assigning one of the units to each of the sections, dividing the sections into a like number of groups, assigning one of the units to each of the groups, and collocating the class, section and group units to form a complete symbol. 30
15. A system of cryptography consisting in selecting a predetermined number of arbitrary symbol units less than the number of letters in the alphabet, dividing the alphabet into classes equal to the number of symbol units, assigning one of the units to each of the classes, dividing the classes into a like number of sections, assigning one of the units to each of the sections, dividing the sections into a like number of groups, assigning one of the units to each of the groups, collocating the class, section and group units to form a complete symbol, employing a card displaying a predetermined number of groups of unit symbols, and designating thereon the units collocated to complete the symbol. 35
16. A system of cryptography consisting in selecting a predetermined number of arbitrary symbol units less than the number of letters in the alphabet, dividing the alphabet into classes equal to the number of symbol units, assigning one of the units to each of the classes, dividing the classes into a like number of sections, assigning one of the units to each of the sections, dividing the sections into a like number of groups, assigning one of the units to each of the groups, collocating the class, section and group units to form a complete symbol, employing a card displaying a predetermined number of separate fields, each having a predetermined number of groups of unit symbols and designating thereon the units collocated to complete the symbol. 40
17. A system of cryptography consisting in selecting a plurality of groups of like arbitrary symbol units similarly sequent and less than the number of letters in the alphabet, dividing the alphabet into arbitrary classes equal to the number of units in one group, assigning to the classes the units of one group, dividing the classes each into sections equal to the number of units in one group, assigning to the sections the units of another group, dividing the sections into groups equal to the number of units in a symbol group, assigning to the groups the units of another symbol group, and collocating the class, section and group units to form a complete symbol. 45
18. A system of cryptography consisting in selecting a plurality of groups of like arbitrary symbol units similarly sequent and less than the number of letters in the alphabet, dividing the alphabet into arbitrary classes equal to the number of units in one group, assigning to the classes the units of one group, dividing the classes each into

sections equal to the number of units in one group, assigning to the sections the units of another group, dividing the sections into groups equal to the number of units in a symbol group, assigning to the groups the units of another symbol group, collocating the class, section and group units to form a complete symbol, employing a card displaying a predetermined number of the groups 5 of unit symbols and designating thereon the units collocated to complete the symbol.

19. A system of cryptography consisting in selecting a plurality of groups of like arbitrary symbol units similarly sequent and less than the number of letters in the alphabet, dividing the alphabet into arbitrary classes equal to the number of units in one group, assigning to the classes the units of one group, dividing the classes each into 10 sections equal to the number of units in one group, assigning to the sections the units of another group, dividing the sections into groups equal to the number of units in a symbol group, assigning to the groups the units of another symbol group, collocating the class, section and group units to form a complete symbol, employing a card displaying a predetermined number of the groups of unit symbols designating thereon the units collocated to complete the symbol 15 and designating a unit of another group, when necessary, to differentiate between words designated by identical class, section and group units.

20. A system of cryptography consisting in selecting a plurality of groups of like arbitrary symbol units similarly sequent and less than the number of letters in the alphabet, dividing the alphabet into arbitrary classes equal to the number of units in one group, assigning to the classes the units of one group, dividing the classes each into 20 sections equal to the number of units in one group, assigning to the sections the units of another group, dividing the sections into groups equal to the number of units in a symbol group, assigning to the groups the units of another symbol group, collocating the class, section and group units to form a complete symbol, employing a card displaying a predetermined number of separate fields, each having a predetermined number 25 of the groups of unit symbols and designating thereon the units collocated to complete the symbol.

21. A system of cryptography consisting in selecting a plurality of groups of like arbitrary symbol units similarly sequent and less than the number of letters in the alphabet, dividing the alphabet into arbitrary classes equal to the number of units in one group, assigning to the classes the units of one group, dividing the classes each into sections equal to the number of units in one group, assigning to the sections the units of another group, dividing the sections into groups equal to the number of units in a symbol group, assigning to the groups the units of another symbol group, collocating the class, section and group units to form a complete symbol, employing a card displaying a predetermined number of the groups of unit symbols designating thereon the units collocated to complete the symbol 30 and designating a unit of another group, when necessary, to differentiate between words designated by identical class, section and group units. 70

22. A system of cryptography consisting in selecting a plurality of groups of like arbitrary symbol units similarly sequent and less than the number of letters in the alphabet, dividing the alphabet into arbitrary classes equal to the number of units 35 in one group, assigning to the classes the units of one group, dividing the classes each into sections equal to the number of units in one group, assigning to the sections the units of another group, dividing the sections into groups equal to the number of units in a symbol group, assigning to the groups the units of another symbol group, collocating the class, section and group units to form a complete symbol, employing a card displaying a predetermined number 40 of separate fields, each having a predetermined number of the groups of unit symbols designating thereon the units collocated to complete the symbol, and designating, when necessary, another unit of another group 45 within the same field to differentiate between words designated by identical class, section and group units. 95

HENRY C. GAUSS.
